CULINARY BEATER

Richard S. Latham, Chicago, Ill., assignor to Ekco Products Company, Chicago, Ill., a corporation of Illinois

Application February 19, 1959, Serial No. 54,674

Term of patent 14 years

(Cl. D44—1)

Fig. 1 is a side elevational view of a culinary beater showing my new design.

Fig. 2 is a similar view as the article appears when turned 90 degrees about its upright axis relative to position shown in Fig. 1.

Fig. 3 is a top plan view thereof.

The essential features of my design reside in the portion shown in solid lines on the drawing.

I claim:

The ornamental design for a culinary beater, as shown and described.
